GESELLSCHAFT, OF WERNERWERK, SIEMENSSTADT, NEAR BERLIN, GERMANY

CIRCUIT ARRANGEMENT FOR STEPPING SWITCHES

Application filed August 18, 1930, Serial No. 475,890, and in Germany October 30, 1929.

The invention relates to stepping switches that are positioned by one or more impulse trains, the number of steps that can be taken by these switches being smaller than the number of impulses transmitted for positioning them.

In the known arrangements these switches are positioned from the normal position by every impulse train. These have the defect that the next impulse train can arrive before the stepping switches have reached their normal position after being operated by the preceding train, or that (to avoid this drawback) the setting up of the connection is retarded until the stepping switches have reached their normal position after every impulse train.

Now the object of the invention is to remove these faults, this being achieved in that the stepping switches are moved on by every impulse train from the position reached owing to the preceding impulse train, the normal position being used like every other position.

The figure shows one method of carrying out the invention. It shows a junction line VL associated with a switch W having the wipers $a_1, b_1, c_1, d_1, e_1, f_1$; the switch can be used for the most diverse purposes, for example, it can serve to designate different traffic routes and also as a selecting device for selecting free trunk lines in one or more traffic directions.

As a device for designating different traffic routes it can also form the switch, which—after a group selector GW positioned over the junction line has been released and after the switching-over to another traffic route has been effected—is reached over the latter route and comprises the same switching device that served to designate the traffic route. After designating has been effected, its positioning can be effected by means of a non-numerical selection like a preselector or it can be done by means of number impulses like a posterior switch.

The details of the circuit will now be described so far as they are of interest.

When the junction line VL is reached by some connecting device, over the c lead a circuit is established, in which the winding I

of relay C is energized and at the same time the feeding bridge relays A and B are energized over the leads a and b , hence, winding II of relay C is placed in a locking circuit over: earth, battery, contact $3\ c$, winding II of relay C, contact $5\ a$, relay V 1, earth. In this circuit relay V 1 is also energized. By operating his number dial, the subscriber can repeatedly interrupt the line loop, in which the feeding bridge relays A and B were energized, and so can, in known manner, position the group selector GW associated with the junction line VL. After the group selector GW has been positioned, other connecting devices beyond the group selector can be positioned by means of number impulses from the calling subscriber, because the interruptions of the line loop are repeated over the junction line VL by the closing of contact $5\ a$ at each impulse.

Besides acting on the different connecting devices, the current impulses transmitted by the subscriber at the same time act on the switch W. If the first impulse train consists of two impulses, the first time relay A is de-energized, the relay V 2 is energized over: earth, battery, contact $3\ c$, contact $4\ a$, winding I of relay V 2, relay V 1, earth; because contact $5\ a$ has momentarily removed the short circuit. Relay V 2 remains energized during the whole impulse train, because the short circuit at each impulse has caused it to work as a slow acting relay, similarly as the relay C, which, during the impulse train, does not fall back owing to the short circuit at contact $4\ a$. At every impulse the rotary magnet D of the switch W is energized at the same time as the driving magnets of the different connecting devices over: earth, battery, rotary magnet D, contacts $44\ v\ 2, 43\ f, 42\ a$ earth. Hence, the wipers of the switch W are moved on two steps. Hence, after relay V 2 has been released owing to being short circuited over its winding I by contact $5\ a$ at the end of the impulse train, the following circuit is established over the wiper $d\ 1$: earth, contacts $23\ c, 24\ v\ 2, 25\ u$, wiper $d\ 1$, contacts $n\ 1, 6\ h\ 1$, relay H 1, battery, earth. Relay H 1 is operated in this circuit and by closing its contacts $7\ h\ 1$ it places itself in a

locking circuit over: earth, contacts 12 *c*, 7 *h* 1, relay H 1, battery, earth. Contact 18 *h* 1 closes a circuit for energizing the relay U over: earth, battery, resistance *W*₁, 5 relay U, contact 18 *h* 1, earth. Hence, contact 25 *u* is opened and contact 26 *u* is closed.

If the next impulse train comprises one impulse, the rotary magnet D of the switch W advances the wipers one step. Hence, the 10 wiper *e* 1 reaches the contact *n* 2, and upon the release of relay V 2 at the end of the impulse train the following circuit is closed: earth, contacts 23 *c*, 24 *v* 2, 26 *u*, wiper *e* 1 of the switch W, contacts *n* 2, 31 *h* 2, relay 15 H 2, battery, earth. The closing of contact 32 *h* 2 places the relay H 2 in a locking circuit over: earth, contacts 27 *c*, 32 *h* 2, relay H 2, battery, earth. Furthermore, contact 16 *h* 2 short circuits relay U, which is released, and after contact 26 *u* has been opened the contact 25 *u* is closed.

The third impulse train consisting of three impulses advances the switch W three steps, so that the wiper *d* 1 reaches the contact *n* 3, 25 over which the following circuit is established after relay V 2 has fallen back at the end of the impulse train: earth, contacts 23 *c*, 24 *v* 2, 25 *u*, wiper *d* 1 of the switch W, contacts *n* 3, 30 *h* 1, 29 *h* 3, relay H 3, battery, 30 earth. By closing its contact 28 *h* 3, the relay H 3 places itself in a locking circuit over: earth, battery, relay H 3, contacts 28 *h* 3, 27 *c*, earth. Relay U now is again energized, because contact 17 *h* 3 removes the short circuit from its winding; contact 25 *u* is opened and contact 26 *u* is closed.

The fourth impulse train consisting of one impulse advances the switch W so that its wiper *e* 1 reaches contact *n* 4, at the end of 40 the impulse train the following circuit is established: earth, contacts 23 *c*, 24 *v* 2, 26 *u*, wiper *e* 1 of switch W, contacts *n* 4, 35 *h* 2, 33 *h* 4, relay H 4, battery, earth. The closing of contact 34 *h* 4 locks the relay H 4 over: 45 earth, contacts 27 *c*, 34 *h* 4, relay H 4, battery, earth. The closing of contact 19 *h* 4 short circuits the relay U, hence, it is released and closes contact 25 *u* after opening contact 26 *u*.

If the next impulse train consists of two 50 impulses, the wiper *d* 1 of the switch W reaches the contact *n* 5, that is to say, its normal position. Therefore the following circuit is closed after the impulse train has ended: earth, contacts 23 *c*, 24 *v* 2, 25 *u*, wiper 55 *d* 1 of the switch W, contacts *n* 5, 11 *h* 3, 9 *h* 5, relay H 5, battery, earth. By closing contact 10 *h* 5, relay H 5 closes a locking circuit for itself, while the opening of contact 20 *h* 5 removes the short circuit from the winding 60 of relay U, and thus this relay is again energized. Hence, contact 25 *u* is again opened and contact 26 *u* is closed.

During the next impulse train, which is assumed to consist of eight impulses, the 65 switch W is moved on eight steps, so that the

wiper *e* 1 reaches the contact *n* 6, over which the following circuit is established at the end of the impulse train: earth, contacts 23 *c*, 24 *v* 2, 25 *u*, wiper *e* 1 of switch W, contacts *n* 6, 38 *h* 4, 36 *h* 6, relay H 6, battery, earth. In 70 this circuit relay H 6 is energized, and by closing its contact 37 *h* 6, it places itself in a locking circuit over: earth, contacts 27 *c*, 37 *h* 6, relay H 6, battery, earth. Relay U is short circuited by the closing of contact 21 *h* 6, hence, it falls back and after having opened its contact 26 *u* it closes the contact 25 *u*. Furthermore, after relay H 6 has been energized, the following circuit is established: earth, winding II of relay V 2, contact segment, wiper *f* 1 of the switch W, contacts 40 *h* 6, 41 *x*, relay Y, battery, earth. Relays V 2 and Y are operated in this circuit, hence, the rotary magnet D of switch W is placed in an automatically operated energizing circuit: earth, battery, rotary magnet D of switch W, contacts 44 *v* 2, 46 *y*, relay interrupter RU, earth. The rotary magnet continues to be operated until the wipers of the switch W have reached their normal position, that is to say, at the moment when the wiper *f* 1 leaves the contact segment the circuit of the relays V 2 and Y is opened, so that the switch is arrested. In the now reached zero position the following circuit 95 is established: earth, contacts 23 *c*, 24 *v* 2, 25 *u*, wiper *d* 1 of the switch W, zero position (= contact *n* 5), contacts 15 *h* 6, 14 *x*, relay X, battery, earth. The relay X is operated in this circuit and by closing its contact 13 *x* 100 it is placed in a locking circuit over: earth, contacts 12 *c*, 13 *x*, relay X, battery, earth.

On being operated, the relay X also opens the contacts 54 *x*, 58 *x*, and 60 *x*, whereby the positioned group selector GW and the succeeding positioned connecting devices are released in some manner, and the junction line VL over the contacts 56 *x*, 57 *x*, 59 *x* is switched onto the wipers *a* 1, *b* 1, *c* 1 of the switch W. One possibility now is that the switch hunts for a connecting device of another traffic route, for example, by closing the contact 47 *x* the relay X establishes an automatic energizing circuit for the rotary magnet D, which is kept dependent on the test relay T of the switch W. When a free connecting device is reached the relay T is operated over the wiper *c* 1 and at contact 48 *t* it opens the energizing circuit of the rotary magnet D. In an alternative arrangement the contacts 47 *x* and 48 *t* are omitted and the switch W is positioned by number impulses like a posterior switch, since the further impulse trains transmitted by the subscriber cause the energizing circuit of the relays A and B to be interrupted at each impulse in the same manner, hence, the number impulses reach the rotary magnet D of the switch W over the contact 42 *a* after contact 44 *v* 2 has been closed.

We see from the description that the switch W, which is positioned by a number of impulses for designating a traffic route or some other purpose, the number of such impulses being greater than the number of its steps; this switch can be used also for other purposes, for example, as a preselector or as a posterior selector.

What is claimed is:

- 10 1. In a telephone system, a stepping switch, means for positioning said switch by one or more impulse trains, said switch having a smaller number of steps than the number of impulses transmitted for positioning it, and means for advancing said switch by every impulse train from the position reached owing to the preceding impulse train. 75
- 15 2. In a telephone system, a stepping switch, means for positioning said switch by one or more impulse trains, said switch having a smaller number of steps than the number of impulses transmitted for positioning it, means for advancing said switch by every impulse train from the position reached owing to the preceding impulse train, and means effective at the conclusion of every impulse train that effects the positioning of said switch for determining the manner in which said switch will continue to operate. 80
- 20 3. In a telephone system, a trunk having access to automatic switches over two branches, means for transmitting trains of impulses for positioning certain of said automatic switches over one of said branches, a rotary stepping switch associated with said trunk adapted to be advanced by every impulse train from the position reached owing to the preceding impulse train, and means controlled by the impulse trains that serve to 85
- 25 position said automatic switches over one branch for positioning said stepping switch to determine over which particular branch the connection is to be established. 90
- 30 4. In a telephone system, a trunk having access to automatic switches over two branches, means for transmitting trains of impulses for positioning certain of said automatic switches over one of said branches, a single level stepping switch associated with said trunk adapted to be advanced by every impulse train from the position reached owing to the preceding impulse train, and means controlled by the impulse trains that serve to 95
- 35 position said automatic switches over one branch for positioning said stepping switch to determine over which particular branch the connection is to be established. 100
- 40 5. In a telephone system, a trunk having access to automatic switches over two branches, means for transmitting trains of impulses for positioning certain of said automatic switches over one of said branches, a single level stepping switch associated with said trunk adapted to be advanced by every impulse train from the position reached owing to the preceding impulse train, and means controlled by the impulse trains that serve to 105
- 45 position said automatic switches over one branch for positioning said stepping switch to determine over which particular branch the connection is to be established, and means including said switch for connecting up automatic switches over said other branch. 110
- 50 6. In a telephone system, a trunk having access to automatic switches over two branches, means for transmitting trains of impulses for positioning certain of said automatic switches over one of said branches, a single level stepping switch associated with said trunk adapted to be advanced by every impulse train from the position reached owing to the preceding impulse train, and means controlled by the impulse trains that serve to 115
- 55 position said automatic switches over one branch for positioning said stepping switch to determine over which particular branch the connection is to be established, and means including said switch for connecting up automatic switches over said other branch. 120
- 60 7. In a telephone system, a trunk having access to automatic switches over two branches, means for transmitting trains of impulses for positioning certain of said automatic switches over one of said branches, a single level stepping switch associated with said trunk adapted to be advanced by every impulse train from the position reached owing to the preceding impulse train, and means controlled by the impulse trains that serve to 125
- 65 8. In a telephone system, a trunk having access to automatic switches over two branches, means for transmitting trains of impulses for positioning certain of said automatic switches over one of said branches, a single level stepping switch associated with said trunk adapted to be advanced by every impulse train from the position reached owing to the preceding impulse train, and means controlled by the impulse trains that serve to 130
9. In a telephone system, a trunk having access to automatic switches in a main exchange and a branch exchange, means for transmitting a plurality of series of impulses over said trunk for positioning switches in said main exchange, a stepping switch having a plurality of wipers, a plurality of registering relays, means responsive to a particular plurality of series of impulses for operating said relays over certain of said

wipers, and means responsive to the operation of all of said relays for establishing a connection over the remaining wipers with an automatic switch in said branch exchange.

- 5 10. In a telephone system, a trunk line extending to a selector switch, means for sending a plurality of series of impulses over said trunk line to operate said selector and succeeding selectors, a branch of said trunk line, 10 a combination register and selector switch responsive to said series of impulses, said combination switch having registering wipers and a set of selector wipers terminating said branch, relays successively operated over said register wipers responsive to particular series of impulses, and means controlled by the last operated one of said relays for disconnecting the trunk line from said selector and for connecting the trunk to said branch.

- 20 11. In a telephone system, a trunk line extending to a selector switch, means for sending a plurality of series of impulses over said trunk line to operate said selector and succeeding selectors, a branch of said trunk line, 25 a combination register and selector switch responsive to said series of impulses, said combination switch having registering wipers and a set of selector wipers terminating said branch, relays successively operated over said register wipers responsive to particular series of impulses, means controlled by the last operated one of said relays for disconnecting the trunk line from said selector and for connecting the trunk to said branch, and means for restoring said combination switch to normal.

- 30 12. In a telephone system, a trunk line extending to a selector switch, means for sending a plurality of series of impulses over said trunk line to operate said selector and succeeding selectors, a branch of said trunk line, 35 a combination register and selector switch responsive to said series of impulses, said combination switch having registering wipers and a set of selector wipers terminating said branch, relays successively operated over said register wipers responsive to particular series of impulses, means controlled by the last operated one of said relays for disconnecting the trunk line from said selector and for connecting the trunk to said branch, means for restoring said combination switch to normal, trunk lines accessible to said set 45 of selector wipers, and means for causing said combination switch to hunt for an idle one of said trunk lines.

- 50 13. In a telephone system, a trunk line, 60 means including a selector switch for extending said trunk line responsive to a series of impulses, a branch of said trunk line terminating in a lineswitch having a rotary movement only, means for operating said lineswitch responsive to said series of impulses, 65 trunk lines accessible to said lineswitch, a reg-

istering device comprising relays for causing said lineswitch to hunt for an idle one of said trunk lines, and wipers on said lineswitch for operating said relays.

- 70 14. In a telephone system, a trunk having access to automatic switches over two branches, means for transmitting series of impulses for positioning certain of said automatic switches over one of said branches, a register responsive to said series of impulses, 75 relays successively operated by said register responsive to a predetermined number of impulses in each of a predetermined number of said series of impulses, each of said relays preparing a circuit for the succeeding relay, and means responsive to the operation of the last one of said relays for disconnecting said trunk from the first one of said branches and for connecting said trunk to the automatic switches over the other of said branches. 80

- 85 15. In an automatic telephone system, a stepping switch, means for positioning said switch by each impulse of one or more series of impulses, said switch having a smaller number of steps than the number of impulses transmitted for positioning it, means for advancing said switch by each impulse of every impulse series from the position reached responsive to the preceding series of impulses, and means responsive to a predetermined 90 number of impulses in each series and a predetermined number of series of impulses for restoring said switch to normal.

- 95 16. In an automatic telephone system, a stepping switch, means for positioning said switch by each impulse of one or more series of impulses, said switch having a smaller number of steps than the number of impulses transmitted for positioning it, means for advancing said switch by each impulse of every 100 impulse series from the position reached responsive to the preceding series of impulses, means responsive to a predetermined number of impulses in each series and a predetermined number of series of impulses for restoring said switch to normal, and means for subsequently causing said switch to automatically advance step by step. 105

- 110 17. In a telephone system, a trunk line, 115 means including a selector switch for extending said trunk line responsive to series of impulses, a branch of said trunk line terminating in a second switch, means for positioning said second switch by each impulse in said series of impulses from the position reached responsive to the preceding series of impulses, trunk lines accessible to said second switch, and means responsive to a predetermined number of series of impulses and a predetermined number of impulses in each of said series for restoring said second switch to normal, disconnecting said trunk line from said selector switch, and for connecting said trunk line to said branch. 120

- 125 18. In a telephone system, a trunk line, 130

means including a selector switch for extending said trunk line responsive to series of impulses, a branch of said trunk line terminating in a second switch, means for positioning said second switch by each impulse in said series of impulses from the position reached responsive to the preceding series of impulses, trunk lines accessible to said second switch, means responsive to a predetermined number of series of impulses and a predetermined number of impulses in each of said series for restoring said second switch to normal, disconnecting said trunk line from said selector switch, and for connecting said trunk line to said branch, and means for subsequently advancing said second switch automatically to find an idle one of said trunk lines accessible to said second switch.

19. In an automatic telephone system, a trunk having two branches, means responsive to a plurality of series of impulses transmitted by a calling subscriber for operating a train of automatic switches over the first of said branches, a rotary stepping switch associated with said trunk positioned by each impulse of said plurality of series of impulses from the off-normal position reached responsive to the preceding series of impulses, and means responsive to a predetermined number of impulses being dialled in each of said series of impulses for releasing the switches over said first branch and for seizing the second of said branches.

20. In an automatic telephone system, a trunk line having access to automatic switches over two branches, means for transmitting a plurality of series of impulses over said trunk line for positioning automatic switches over one of said branches, a stepping switch having two wipers and associated banks, relays connected to said banks, means responsive to said series of impulses for alternately operating relays connected to each of said banks, each of said relays preparing the circuit for the succeeding relay, and means responsive to the operation of the last relay for restoring said stepping switch to normal and for connecting said trunk to said automatic switches over said second branch.

50 In witness whereof, I hereunto subscribe my name this 22nd day of July, A. D. 1930.

WALTER KUSCHE.
